UNITED STATES PATENT OFFICE.

JOHN L. SETTY, OF NORTH UNIONTOWN, OHIO.

CAR-COUPING.

SPECIFICATION forming part of Letters Patent No. 340,735, dated April 27, 1886.

Application filed September 26, 1885. Serial No. 173,295. (No model.)

To all whom it may concern:

Be it known that I, JOHN L. SETTY, of North Uniontown, in the county of Highland and State of Ohio, have invented a new and 5 Improved Car-Coupling, of which the following is a full, clear, and exact description.

My invention relates to the construction of car-couplings, its object being to provide an automatic coupling; and to this end the invention consists of a sliding plate which is moved forward so as to come beneath the point of the coupling-pin by the action of the lever employed to raise said pin; and the invention consists of certain details of construction and combinations of parts, to be hereinafter described, and specifically pointed out in the claims.

Reference is to be had to the accompanying drawings, forming part of this specification, in which similar letters of reference indicate corresponding parts in all the figures.

Figure 1 is a side view of my improved car-coupling, the draw-head being shown in vertical section to disclose the construction and 25 arrangement of the interior parts. Fig. 2 is a plan view of the device, the lever-standard, lever, and coupling-pin being shown in section; and Fig. 3, a detail view of a modified form of sliding plate.

30 The draw-head A, which is secured to the car in the ordinary manner, is formed with the usual style of hole, a, for the coupling-pin B to rest in. Upon the top or upper side of the draw-head there is a heavy boss, b, between 35 which and the draw-head proper there is formed a longitudinal groove or channel, c, extending as far forward as the hole a. A sliding plate, d, rests within the channel c and projects outward beyond the boss b. Through 40 this plate d there is passed a downwardly-projecting pin, C, which rides in a narrow perpendicular slot, f, formed in the draw-head just back of the hole a.

The coupling-pin B is connected by a chain, 45 g, with a lever, N, a second chain, g', reaching upward from the lever to within reach of the train-men. This lever N is formed with an arm, N', and pivotally mounted in a standard, M, which projects upward from the boss b, the 50 position and formation of the parts being such that when the lever N is raised the lower end, n, of the arm N' will strike against the heel of

the plate d and force it forward beneath the point of the pin B, as shown in full lines in Fig. 1.

When the parts are in the position just referred to, they are ready to receive the coupling-link D, which is carried by the draw-head of another car, (not shown in the drawings,) for as the link D enters the draw-head A its forward end will strike against the pin C, which will be carried back in the slot f, and this movement of the pin C will carry back the plate d, thus leaving the pin B free to drop into the slot of the coupling-link D. When the pin B is withdrawn to uncouple the cars, the movement of the lever N and its arm N' will again force the plate d forward beneath the point of the pin B, thus automatically setting the coupling.

The slot f is covered by a trap, o, which prevents snow, cinders, &c., from interfering with the working of the parts.

In Fig. 3 I illustrate a modified form of sliding plate, wherein the main body of the plate is thicker and heavier, a small lug or point, d', being arranged to enter the hole a to support the pin B.

Although such a coupling as I have described is entirely automatic in its action, it may be used in connection with the ordinary form of coupling, and consequently cars supplied with my invention may be placed in any train where coupling-links are used.

Having thus described my invention, what I claim as new, and desire to secure by Letters Patent, is—

1. The combination, with the draw-head and its coupling-pin, of a sliding plate, d, having a downwardly-projecting pin, C, a lever, N, connected to the coupling-pin, and having an arm, N', substantially as described.

2. The combination, with the draw-head and its coupling-pin, of a sliding plate, d, having a point, d', and being provided with a downwardly-projecting pin, C, a lever, N, connected to the coupling-pin, and having an arm, N', said lever being mounted on a standard, M, substantially as described.

JOHN L. SETTY.
